FIG. 1.

FIG. 2.

FIG.3.

FIG.4.

FIG.5.

FIG.7.

FIG.8.

FIG.6.

FIG. 1 is a front perspective view of a chair seat showing my new design, comprising side flanges adjacent the rear thereof.

FIG. 2 is an enlarged fragmentary view of one of the two symmetrically identical side flanges thereof.

FIGURE 3 is a front perspective view of the chair of FIGURE 1 wherein grooves are formed in the side flanges from end to end thereof.

FIG. 4 is an enlarged fragmentary view of one of the two symmetrically identical side flanges of FIG. 3.

FIGURE 5 is a front perspective view of the chair of FIGURE 1 wherein grooves are formed in the side flanges terminating inwardly of the ends thereof.

FIG. 6 is an enlarged fragmentary view of one of the two symmetrically identical side flanges of FIG. 5.

FIGURE 7 is a sectional view taken along the lines 7-7 of FIGURE 6.

FIGURE 8 is a sectional view taken along the lines 8-8 of FIGURE 6.

The dominant features of my design reside in the portions shown in full lines on the drawing.

This application is a continuation of my three prior copending applications filed July 20, 1960, Serial Numbers D. 61,443 to 5 inclusive, now abandoned.

I claim:

The ornamental design for a chair seat, as shown and described.
